UNITED STATES PATENT OFFICE.

LESTER L. ISRAEL, NOW BY JUDICIAL CHANGE OF NAME LESTER L. JONES, OF ORADELL, NEW JERSEY, ASSIGNOR TO EMIL J. SIMON, OF NEW YORK, N. Y.

ELECTRICAL COIL APPARATUS.

Application filed August 5, 1919, Serial No. 315,386. Renewed April 13, 1923.

To all whom it may concern:

Be it known that I, LESTER L. ISRAEL, now by judicial change of name LESTER L. JONES, a citizen of the United States, residing at Oradell, in the county of Bergen and State of New Jersey, have invented certain new and useful Improvements in Electrical Coil Apparatus, fully described and represented in the following specification and the accompanying drawings, forming a part of the same.

The invention relates to electrical coil structures, and especially to adjustment means for such coils. The general object is to provide improved and simplified means for effecting a plurality of relatively "broad" adjustments of a coil, or step-by-step adjustments of definite interval, and for effecting a "continuous," or "fine" adjustment, of indefinite gradations, for each of the step adjustments.

Coil mechanism embodying the invention is useful in various kinds of electrical apparatus. In certain of its embodiments the invention is especially advantageous in wireless transmission apparatus. The invention will be herein described with reference to its utility in that art.

As adapted for radio-transmitters, the invention provides an improved wave-changing apparatus, especially suitable for transmitters of the quenched-spark type, although it is adaptable to other types of transmitters.

An important object is to provide for continuous, or indefinite variable, tuning of the antenna circuit at or in the region of a number of different wave length adjustments, by manipulation of one controlling device. Another object is to provide means by which the single controlling handle is engaged with the proper tuning element by the action of the wave changer switch, and is at the same time disengaged from all the other tuning elements. A further object is to provide means by which the continuous tuning of the antenna at or near one wave length is independent of the tuning for each other wave length, so that tuning for a series of three or more wave lengths may be rapidly effected, each independently of the

other, and in any order. A further object is to simplify, and increase the efficiency of the electrical circuit by eliminating a number of high tension leads in the antenna circuit.

In previous forms of apparatus, the primary inductance coil, the antenna coupler coil and the antenna load coil have been provided with a plurality of contacts, and switches have been provided to connect with these contacts to vary the inductance of the different coils simultaneously, and in some cases a common switch-operating mechanism has been provided to move all the switches simultaneously to insure the proper simultaneous adjustment of the coils. A plurality of independent tuning devices or variometers corresponding to the number of wave lengths have been provided for the antenna inductance, and each of these devices has been controlled by a separate handle. To tune for any given wave length, therefore, the operator has always been obliged to notice carefully the position of the wave length switch in order to determine what wave length was effective, and then to note the variometer handle corresponding to that wave length in order that the proper tuning handle might be manipulated. In case of an error in selecting the handle, there was delay in tuning, and also frequently the tuning of the antenna for other wave lengths was interfered with needlessly, requiring their readjustment.

In previous systems also it has been necessary to provide high tension leads connecting the wave length switch contacts with the sliding tuning devices or variometers. It has been difficult to dispose of these leads, so that they would not spark to the coils, and so that they were outside the magnetic field of the coils.

In my invention the first difficulty is avoided by providing a single manipulating device for the various tuning devices or variometers, and in whatever position the wave changing switch may be, manipulation of the tuning device will always effect tuning for that wave length, because the positioning of the wave-changing switch automatically connects the controlling device with

the corresponding variometer. The second difficulty is avoided because the high tension leads are eliminated and one metallic part serves as the wave length switch arm 5 and connector.

The objects, characteristics and advantages of the invention are further explained, so far as is necessary, in connection with the following detailed description of a representative structure embodying my invention. After considering this, it will be evident to persons skilled in the art that the invention may be embodied in different structures, and I do not limit myself to details except as claimed.

Fig. 1 is a diagram of the radio-frequency circuit of a wireless telegraph transmitter of the quenched-spark type, embodying the invention.

Fig. 2 is a section in an axial plane of the aerial wave changing and tuning mechanism.

Fig. 3 is a transverse section of the same.

Fig. 4 is a sectional detail of the sliding contact and connector, and part of one of 25 the variometer arms.

P is the primary inductance with fixed contacts p. S is the secondary inductance or coupling coil with fixed contacts s. Movable contacts p', s' respectively, for these 30 coils are mechanically connected as diagrammatically indicated by shaft 5 to be moved together. L is the antenna load coil, in this case consisting of a flat strip formed in a helix, although it may be of any suitable 35 form and arrangement. Within this coil is a rotatable sleeve 6 of insulating material, and within the sleeve is an endwise reciprocable and rotatable cylindrical rack 7 carrying a movable contact and connector 8 which serves to make the circuit connection 40 for the different wave lengths and at the same time to connect the tuning devices for the different wave lengths mechanically with the tuning handle 9. A pinion 10 effects the 45 endwise reciprocal movement of the rack 7, and this pinion may be connected to move in unison with contacts p', s' by suitable mechanical connections, such as shaft 11 and universal joint 12.

Load coil L is located between suitable insulating end plates 13, 14, and is supported by insulating struts 15 which connect the plates. Secured to plate 14 is a fitting 16 which provides a bearing at 17 for one end 55 of sleeve 6. The other end of the sleeve has a bearing in a fitting 18 supported by end plate 13.

Variometer or tuning arms 20 are provided in number equal to the number of 60 wave lengths. Each of these arms has a clip or sliding contact 21 comprising pairs of fingers 22 embracing the coil strip. These fingers are carried on pivot 23, and the pivot has a stem 24 extending into and secured in 65 the end of an inner sleeve 25 of the vari-

ometer arm. Sleeve 25 telescopes in an outer sleeve 26. The contact is urged out into proper engagement with the coil by a spring 27 located within the sleeves and bearing against the bottom of sleeve 26 and against a plug 28 in the outer end of sleeve 25. This plug also accommodates the pin 24 of the contact pivot. The inner end of sleeve 26 is formed into a fork 29, the ends of which are connected pivotally by means of eyes 30 to 70 trunnions 31 on a divided ring 32 which embraces sleeve 6 and is revoluble thereon. Each ring may be in two parts secured together by screws 33.

The conductive continuity of the ring is 80 preferably broken by inserting in the ring at at least one point of its circumference an insulating disk or washer 33^a, and also properly insulating the adjacent screw 33 with insulating sleeves 33^b and washers 33^c, 85 to prevent the circulation in the ring of electrical currents caused by induction.

The rings have inwardly projecting members 34 located between shoulders 35 on sleeve 6 to locate the rings lengthwise on the 90 sleeve. Each of the inwardly projecting members 34 has, usually at two opposite points of its circumference, notches 36 providing shoulders for engagement with connector 8.

Cylindrical rack 7, beginning at the outer end and for the greater part of its length is tubular. At the other end adjacent to connector 8 the rack has a plain round solid extension 40 on the end of which is secured 95 a disc 41 of insulating material, having a sliding fit in sleeve 6 to guide the end of the sleeve to turn in accordance with rotation of the rack. Disc 41 has secured to it at one side a lug 42, fitting in a longitudinal slot 43 in one side of sleeve 6, thus causing the sleeve to turn in accordance with rotation of the rack. Connector 8 is in the form of a spring-pressed plunger movably mounted in a sleeve 44 located in a transverse bore of 100 rack extension 40. A spring 45 located within sleeve 44 urges the connector plunger outward in slot 43. A pin 46 engaging slots 47 in one end of sleeve 44 limits outward 105 movement of the plunger. The plunger 8 moves along in slot 43 in accordance with endwise movement of rack 7. When it comes opposite any inwardly projecting annulus 34 of one of the variometer rings 32, the plunger is depressed slightly, and if the 110 rack is retained in that position, electrical contact is made with the corresponding variometer arm corresponding to the wave length adjustment of the primary and secondary inductance coils P and S. If sleeve 115 6 is then rotated, plunger 8 slides around the inner periphery of annulus 34 until it encounters one of the notches 36, whereupon it enters the notch, and then the variometer arm is coupled to the sleeve mechanically 120 125 130

and may be rotated with the sleeve to tune the load coil for the corresponding wave length. The sliding contact 21 of the variometer arm has sufficient frictional engagement with the coil to normally hold the variometer arm in position and permit the sleeve 6 to turn within its ring 32 without affecting the variometer arm, unless plunger 8 is in engagement with a notch of corresponding ring 32, and in that case the friction of the contact 21 is overcome and the arm moves with the sleeve, as above described.

Evidently, by successive positioning of rack 7 and plunger 8, connection may be effected with all of the variometer arms in turn, and each of them may be adjusted in the manner described. When all of the arms are once adjusted to correctly tune the aerial circuit with the inductance coils in accordance with variable conditions of the aerial, the load depth of a ship on which the apparatus is placed, or other variable conditions, all of the different tunings will be maintained so long as sleeve 6 is not involved, and the wave length may be quickly changed at will without affecting tuning by reciprocating rack 7.

The pivoted fork connection of the variometer arms with their rings 32 permits each arm to swing in an axial direction over approximately one-third of the coil. This in turn permits the normal angular positioning of certain ones of the variometer arms, as shown in the drawing, in order to locate the coil, sleeve 6, and associated parts in the most convenient relative positions. The telescoped arrangement of the parts of the variometer arms, and springs 27 serve not only to provide the necessary frictional contact with the coil, but to permit the variation in length of the variometer arms due to their different angular positions.

The tubular end of rack 7 has a sliding fit in fitting 16. In the open end of the rack is secured a block 50 having an angular or splined hole, and in this hole is slidably fitted a rod 51 having a similar cross-section. The outward end of the rod is secured in an insulator 52. A stem 53 is secured in the other end of the insulator and tuning wheel 54 or handle 9 is secured on this stem. A bracket 54 is located on a plate 55 secured to plate 14 by struts 56, and this bracket surrounds insulator 52 and has a bearing 57 for stem 53, and also prevents end movement of handle 9 and rod 51 in an obvious way. Plate 55 has a central hole 58 to accommodate the end of rack 7.

Pinion 10 has its shaft 60 mounted in bearings formed in extensions 61 of fitting 16.

The binding post or connection 65 on rear plate 13 has metallic connection with the rear end of the load coil, and fitting 16 has a binding post or connection 66.

The electrical circuit of the antenna in-

ductance in the position of parts shown in Fig. 2 is from the aerial to binding post 65, through one-half of the rear turn of the inductance coil L, then through the variometer contact sleeves and ring 32 to connector 8, through rack 7 to fitting 16 and binding post 66, and then as shown in the diagram, Fig. 1, through coupling coil S to ground. It will be noted that there is a liberal air gap between rack 7 and the other rings 32 which are in electrical contact with the coil. This is sufficient to prevent leakage of current from unused turns of the coil in which potential is created by induction. The weakest insulation path is along sleeve 6. When the rack is moved forward so that connector 8 is in engagement with the foremost ring 32 and all of the inductance coil is in use. In convenient design of the apparatus, it is practicable to provide at least five inches total insulation distance along this sleeve to the rearmost ring, which is sufficient to prevent leakage or sparkover due to the high voltages along the coil, which are brought to the sleeve by the variometer arms 20. When the connector 8 is in engagement with any of the other rings 32, the insulation path is shorter, but also the voltage developed is proportionally less. Furthermore, the spacing of the rings may obviously be sufficient to prevent sparkover between adjacent rings.

Insulator 52 serves to insulate the high tension electrical system from tuning handle 9, which is kept at ground potential by its metallic connection with the grounded bracket 54.

In some cases it is desirable to short circuit unused portions of the coil to avoid phenomena known as "end effect", due to induction. This is done by providing the outermost ring 32 with a contact finger 70, which has a sliding engagement with peripheral part 71 of metal fitting 16. When contact 8 is in engagement with any variometer ring other than the outermost one, the unused part of the coil is short circuited through the outermost variometer arm, its ring 32, contact 70, fitting 16, rack 7 and contact 8.

Similar principles of construction and arrangement may be applied to systems employing flat or conical spiral coils, with suitable modifications of mechanical details to suit such arrangement.

It will be understood from the foregoing that before commencing sending, the operator may turn the antenna coil for all wave lengths by moving the wave-changing switch to successive positions, and in each of its positions rotating the turning handle 9 appropriately to suit the present condition of the aerial circuit. He may then use any wave length immediately by moving the wave-changing switch, and in whatever position it may be he can retune the load coil

whenever it may be necessary by moving handle 9 without the possibility of interfering with tuning for other wave lengths.

What is claimed is:

5. 1. Electrical-coil adjustment apparatus, comprising a coil, a plurality of movable contacts engaging the coil at different points, a controlling device for adjusting said contacts, and means for electrically connecting 10 the controlling device with the contacts selectively.
  2. Electrical-coil adjustment apparatus, comprising a coil, a plurality of movable contacts engaging the coil at different 15 points, a controlling device, and means for establishing electrical connection with the coil through the individual contacts selectively, and simultaneously effecting mechanical connection between the selected contact 20 and the controlling device for the adjustment of that contact without disturbing the adjustment of the other contacts.
  3. In electrical-coil adjustment apparatus, the combination of a coil, a rotatable member near the coil, a plurality of variometer devices in disconnected relation to the rotatable member and each having movable contact with a portion of the coil, a connector, means for shifting the connector 25 to engagement with the variometer devices selectively, and a single controlling member operative to adjust the variometer device with which the connector engages without disturbing the other variometer devices.
  4. In electrical-coil adjustment apparatus, the combination of a coil, a rotatable sleeve near the coil, a plurality of variometer devices in disconnected relation to the rotatable sleeve and each having movable contact with a portion of the coil, a longitudinally and rotatably movable member 30 within the sleeve, a connector carried by said member to engage said variometer devices selectively, means for moving said member longitudinally to effect said selective engagement, and a rotatable controlling device to rotate said member to effect coil adjustment through the variometer device with which the connector is engaged without disturbance of the other variometer devices.
  5. In electrical-coil adjustment apparatus, the combination of a coil, a rotatable sleeve 45 adjacent to the coil, the sleeve having a longitudinal slot, a member mounted within the sleeve for relative reciprocal and rotary movement, a yieldable connector carried by said member and located in said slot, means for moving said member longitudinally, independent means for rotating said member, variometer rings definitely spaced lengthwise of the sleeve and rotatable relatively thereto, said rings having shoulders to be
  6. In electrical-coil adjusting apparatus, the combination with a coil, of a shiftable member, means positioned by said shiftable member for selectively establishing electrical connection with the coil at a plurality of relatively widely separated points, and means operated by further positioning of said member for varying by indefinite gradations the adjustment of any connection selected. 65
  7. In electrical-coil adjusting apparatus, the combination with a coil, of a shiftable conducting member adjacent to the coil, and a shiftable connecting means comprising a part rotatable about the axis of said conducting member, an arm pivotally connected to said part, and a contact member carried by the arm and engaging the coil. 70
  8. In electrical-coil adjusting apparatus the combination with a coil, of a shiftable conducting member adjacent to the coil, shiftable connecting means comprising a part rotatable about the axis of said conducting member, an arm pivotally connected to said part, and a contact member carried by said arm and engaging the coil, the arm being formed to permit its length to vary automatically in accordance with its 75 angularity. 85
  9. An adjustable coil mechanism, comprising a coil, a rotatable controlling member, a ring revolvable about the controlling member, a fork pivoted to the ring, a yieldably extensible arm carried by the fork, and a contact member at the end of the arm engaging the coil. 90
  10. In electrical-coil adjusting apparatus, the combination with a coil, of connecting means comprising a member movable for making broad adjustment of the amount of the coil connected in circuit and otherwise adjustable for fine adjustment by varying by indefinite gradations the amount of the 95 coil inserted. 105
  11. In electrical-coil adjusting apparatus, the combination with a coil, of connecting means comprising a member movable axially of the coil for making broad adjustment of the amount of the coil connected in circuit and movable rotatably to vary by indefinite gradations the amount of the coil inserted. 110
- In testimony whereof I have hereunto set my hand in the presence of two subscribing 120 witnesses.
